UNITED STATES PATENT OFFICE.

CLARK F. RIGBY, OF MANNINGTON, WEST VIRGINIA.

SLIDE-VALVE.

SPECIFICATION forming part of Letters Patent No. 663,300, dated December 4, 1900.

Application filed December 8, 1899. Serial No. 739,614. (No model.)

To all whom it may concern:

Be it known that I, CLARK F. RIGBY, a citizen of the United States, residing at Mannington, in the county of Marion and State of West Virginia, have invented new and useful Improvements in Slide-Valves, of which the following is a specification.

This invention relates to a double-balanced slide-valve, and has for its object to provide a valve which will automatically expand and contract with its seats and remain constantly tight thereon without sticking.

The invention consists in the novel features of construction and in the combination and arrangement of parts hereinafter fully described and claimed, and illustrated by the accompanying drawings, in which—

Figure 1 is a vertical longitudinal sectional view of an engine-cylinder and steam-chest provided with my improvement. Fig. 2 is a sectional plan view on line 2 2 of Fig. 1, and Fig. 3 is a vertical cross-section on line 3 3 of the same figure.

1 is the cylinder, 2 the steam-chest, and 3 the downwardly-converging valve-seats formed by the inner faces of the sides of chest 2. Arranged centrally in each valve-seat is an exhaust-port 4 and on either side of said exhaust-port a port 5, the latter leading to opposite ends of the cylinder.

The valve consists of two longitudinal members 6 and 7, having their outer longitudinal faces inclined complementary to the converging seats 3, with which they maintain a close fit. The valve members are recessed on their inner sides to form cavity 8 and are formed adjacent their ends with vertical interlocking tongues 6' and 7', respectively. Arranged in cavity 8 and bearing on the opposite faces of the valve members are expandable springs 9, which hold the valve members constantly to their seats. The interlocking tongues 6' and 7' hold the members in proper relative position and balance them one against the other in such manner as to prevent excessive steam-pressure from binding them to the seats. 10 is the link connecting the valve and valve-gear. On the outer face of each valve member is depression 11 for covering the cylinder-ports 5 alternately with exhaust-port 4.

In practice the valve is made with its members tightly interlocking and without the

transverse play indicated in the drawings. It is then fitted tightly in operative position between the previously-heated valve-seats, and 55 the latter, being heated, are expanded, as in actual practice. After being thus fitted the valve is removed and edges or faces 12 and 13 of valve member 6 and tongues 6' are planed off, so that when the steam-chest and valve-seats 60 contract, as when cooling, the valve will contract therewith against the pressure of springs 9, the latter tending all the while to hold the valve members to their seats. As the ports on opposite sides of the valve are of the same 65 area, as are also the ports of the opposite valve-seats, steam-pressure on the valve is equalized. The valve members are in interlocking engagement from top to bottom of the valve, and hence it is impossible for the valve to twist 70 or become distorted transversely as the result of unequal steam-pressure on its upper and lower portions. Such unequal pressure would occur if the steam-ports were above or below the vertical center of the valve or if 75 the ports were of irregular form—as, for instance, larger at the top than at the bottom—in which case there would be greater pressure on the upper than on the lower portion of the valve, and the effect of such inequality of 80 pressure or lack of balance would be to cause the interlocked tongues to bind each other, and thereby defeat the adjustment for which they are provided, and also would cause the valve to wear unevenly, faster at the top than 85 at the bottom, or vice versa.

A slide-valve constructed as here shown and described is always tightly fitted to the seats and responds to contraction and expansion of the latter without sticking. 90

Having thus fully described my invention, what I claim as new, and desire to secure by Letters Patent, is—

1. In a slide-valve, the combination of opposite valve-seats, a longitudinally-divided valve operative between and on the seats, one of the valve-sections being formed on its inner face with the inturned tongues 7' extending vertically from top to bottom of the valve, and the other valve-section formed 95 with the outwardly-turned tongues 6' extending vertically from top to bottom of the valve, said tongues 7' and 6' interlocking to limit the expansion of the valve uniformly from top 100

to bottom, and means for holding the valve normally expanded, substantially as shown and described.

2. In a slide-valve, the combination of opposite valve-seats, a vertically and longitudinally divided valve operative between and on the seats, vertical interlocking tongues adjacent the ends of the valve members and extending from top to bottom thereof, and springs arranged transversely between the valve members and intermediate the interlocking tongues and pressing outwardly on the valve members, substantially as shown and described.
- 15 3. In a slide-valve, the combination of opposite valve-seats, a vertically and longitudinally divided valve operative between and on the seats, the valve being formed between its ends with an internal cavity, springs confined in the cavity and pressing outward on the valve members, and vertical interlocking tongues on the inner faces of the valve members adjacent their ends, substantially as shown and described.

dinally divided valve operative between and on the seats, the valve being formed between its ends with an internal cavity, springs confined in the cavity and pressing outward on the valve members, and vertical interlocking tongues on the inner faces of the valve members adjacent their ends, substantially as shown and described.

In testimony whereof I have hereunto set 25 my hand in presence of two subscribing witnesses.

CLARK F. RIGBY.
